R. HARGRAVES

CAN HOLDER AND OPENER

Filed April 18, 1922

FIG. 1

26 30 28 — FIG. 2

INVENTOR.

ROBERT HARGRAVES.

BY

Lockwood Lockwood

ATTORNEYS.

UNITED STATES PATENT OFFICE.

ROBERT HARGRAVES, OF INDIANAPOLIS, INDIANA.

CAN HOLDER AND OPENER.

Application filed April 18, 1922. Serial No. 555,060.

To all whom it may concern:

Be it known that I, ROBERT HARGRAVES, a citizen of the United States, and a resident of Indianapolis, county of Marion, and 5 State of Indiana, have invented a certain new and useful Can Holder and Opener; and I do hereby declare that the following is a full, clear, and exact description thereof, reference being had to the accompanying 10 drawings, in which like numerals refer to like parts.

This invention relates to a combination can holder and opener.

The chief object of the invention is to provide 15 means for holding a can while the cover or top thereof is being cut to open said can.

Another object of the invention is to provide 20 a base for the same which may be rigidly secured to a supporting bench or table, the entire device being of a character which is adapted for use in bakeries, restaurants, cafeterias, hotels and the like, thereby distinguishing the invention from 25 the ordinary hand can openers.

The chief feature of the invention consists in a base which supports the can holding construction and a can opening construction.

The full nature of this invention will be 30 understood from the accompanying drawings and the following description and claims.

In the drawings Fig. 1 is a top plan view 35 of the invention, the dotted lines indicating one of the customary positions of the opening mechanism. Fig. 2 is a side elevational view of the device showing the same associated with a can and a support, the dotted lines indicating the receiving position of the can opening mechanism and the can holding mechanism.

In the drawings 10 indicates a supporting bench or table and herein an arcuate foot 11 is adapted to be rigidly secured to said table by suitable means such as the 45 screws 12. The central projection 13 is similarly secured by the screw 14 and thus the base is rigidly secured to the table. As shown by the sectioned portion in Fig. 2 a groove 15 is provided in the arcuate base 50 for the reception of the enlarged portion 16 of the can 17. If desired the arcuate portions 11 may be provided with elevated portions or retainers 18 which constitute bumpers when the can is positioned adjacent the base. Extending upwardly from

the base is an upright 19 and said upright is cut away at 20 to receive the upper end 21 of the can 17. Extending outwardly from the upright 19 and in a plane intermediate the ends of the can 16 and 21 is 60 a pair of arms 22 which are arcuately formed and serve to receive the can 17.

The means for holding the can during the cutting operation herein consists of a semi-circular member 23 which herein is pivotally 65 supported at each end by and upon each end of the arcuate members 22 and 24. The semi-circular member 23 is provided with a central projection or handle 25 and herein said handle 25 is shown 70 positioned angularly of the semi-circular embracing portion. From Fig. 2 it will be observed that when the handle 25 is in the dotted line position the can 17 may be positioned in the embracing arms 22 75 and adjacent the base 11. Therefore, the handle 25, when moved to the full line position, causes the semi-circular or arcuate member 23 to engage the can and hold the same from tilting movement or escapement. 80

The can is thus rigidly supported for cutting or opening. Herein but one form of the pivotal can engaging construction has been described, although other forms may be utilized and said other forms do not 85 necessarily have to be pivotally supported by the arcuate arms 22 but may be supported upon the standard 19 or an extension thereof.

The cutting or opening means herein 90 illustrated comprises an overhanging supporting portion 26 which provides a pivotal bearing 27 having a pivot pin 28. The pivot pin 28 is supported in the bearing 27 and adjustably thereof as well. Said adjustable 95 support is secured by the retaining washers 29 which are rigidly secured upon said pin 28 by the wing bolts or thumb screws 30. The lower end of the pivot pin 28 which is positioned above the can 17 when the can 100 is in held relation, is slotted to receive a cutting member 31 which is pivotally supported therein at 32. The cutting member 31 consists of a cutting knife or tool 33 which is adjustably supported in a socket 34 105 in said member 31 and by a thumb screw or wing bolt 35. The handle portion 36 is a continuation of the member 31 and when said handle is moved about the pivotal support 27, the knife 33 will cut the top or 110

cover from the can 17 and thereby open the can.

It will be apparent from the full and dotted line positions shown in Figs. 1 and 2, 5 that when the parts are in the dotted line positions the device is adapted to receive a can and that when the parts are in the full line position the device is holding and opening a can. While but one form of cutting 10 mechanism is shown herein, it is to be noted that other forms of cutting mechanisms may be utilized and these may not only be pivotally supported upon one but also upon two axes, as herein shown, and the same may 15 be otherwise supported, to wit upon a third pivotal axis.

The invention claimed is:

1. A can holder and opener including a base, a standard extending upwardly from the base, a curved clamping member pivotally supported at its ends upon an axis transverse to said standard for clamping the can against said standard, an overhanging arm carried by said standard, a cutting device, and means pivotally supporting said cutting device upon said arm, the cutting device being movable into position adjacent the standard to permit the clamping member to be tilted upwardly adjacent thereto substantially as and for the purpose described.

2. A device of the character described in claim 1, characterized by the means which

pivots supports the cutting device upon said arm pivotally supporting said device upon an axis parallel to the standard for 35 cutting purposes and upon an axis transverse thereto and in a plane substantially parallel to the pivotal support of the clamping member, whereby the clamping member may be tilted upwardly after the cutting 40 member has been tilted upwardly to permit the quick insertion and removal of cans from the device.

3. A can holder and opener including a base, a standard extending upwardly from 45 the base, a curved clamping member pivotally supported at its ends upon an axis transverse to said standard for clamping the can against said standard, an overhanging arm carried by said standard, a cutting device, 50 means pivotally supporting said cutting device upon said arm, the cutting device being movable into position adjacent the standard to permit the clamping member to be tilted upwardly adjacent thereto substantially as and for the purpose described, and hand-engageable means upon said clamping member 55 and positioned intermediate the pivotal support at the ends of the curved clamping member.

In witness whereof, I have hereunto affixed my signature.

ROBERT HARGRAVES.
